UNITED STATES PATENT OFFICE.

LESLIE E. MAUPIN, OF CAMPBELLSVILLE, KENTUCKY.

CALCULATOR.

1,414,198.

Specification of Letters Patent. Patented Apr. 25, 1922.

Application filed June 24, 1920. Serial No. 391,445.

To all whom it may concern:

Be it known that I, LESLIE E. MAUPIN, a citizen of the United States, residing at Campbellsville, in the county of Taylor and State of Kentucky, have invented certain new and useful Improvements in Calculators; and I do hereby declare the following to be a full, clear, and exact description of the invention, such as will enable others skilled in the art to which it appertains to make and use the same.

The present invention relates to a tabular calculator for conveniently terminating calculations, such as required in the exchange of grain and sale of flour, meal, and the like, and the invention aims to provide such a device comprising a cylinder containing the tables of calculations or figures and novel means for supporting same for rotation.

20 A further object is the provision of such a device having means for conveniently rotating the cylinders by hand, and means for cooperation with the graduations on the cylinder for convenience in determining the 25 calculations.

It is also the object of the invention to provide a calculator of the nature indicated which is simple and inexpensive in construction, as well as practical and serviceable in 30 use.

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawings, wherein:

Figure 1 is a front view of the device, portions being broken away.

Fig. 2 is a plan view thereof.

Fig. 3 is a vertical section taken on the 45 line 3—3 of Fig. 2, portions being broken away.

The device comprises a vertical cylinder 6 of sheet metal or other suitable material and of suitable diameter and length, which 50 is supported from a vertical board or back 7 to which upper and lower outstanding brackets 8 and 9, respectively, are secured above and below the cylinder. The cylinder has a vertical axle 10 whose terminal portions are journaled for rotation in the brackets, and said axle has its shoulder 10' seating

on the lower bracket to support the axle and cylinder. The cylinder has disks 11 and 12 therein near but spaced from its upper and lower ends, respectively, and secured to the 60 axle, the disks having marginal flanges 13 secured to the cylinder, thus supporting the cylinder from the axle.

In order to conveniently rotate the cylinder, it is provided near its lower end with 65 an annular series of outstanding knobs or finger pieces 14 which can be conveniently grasped by the thumb and finger for turning the cylinder in either direction at any side thereof.

A vertical strip 15 extends longitudinally along the cylinder at the front thereof, and its upper end is secured to the forward end of the bracket 8, as at 16, while the lower end portion of the strip is offset forwardly, 70 as at 17, for the passage of the knobs 14, the lower terminal of the strip being secured on the forward end of the lower bracket 9, as at 18. The strip 15 is close to the cylinder, and in connecting the ends of the brackets 75 8 and 9, will serve as a brace for the frame of which the strip constitutes a part.

The strip 15 cooperates with the graduations on the circumference of the cylinder 6, and in the arrangement shown, the strip 80 15 is provided along one edge with a series of graduations 20 indicating the amount of purchase from five cents up, which preferably runs to eight dollars. The circumference of the cylinder has an annular series of vertical columns 21 containing pounds and fractions thereof to be sold, with the prevailing price per hundred pounds at the heads of the columns, as at 22. Each column is graduated according to the price per hundred 85 pounds up to one hundred pounds, so that when the column is brought adjacent to the column 20 on the strip 15, the graduations of the column 20 will cooperate with the graduations in the corresponding column 21, to indicate at a glance on the column 90 20 the price for a given number of pounds from the column 21, or the number of pounds in the column 21 for a given price from the column 20. An indicator card 23 100 is clamped to the cylinder at the upper end thereof, by means of a clip 24, and has a pointer 25 indicating the column containing the price per hundred pounds prevailing for the time being and the card also contains the 105 name of the commodity sold. It is thus an easy matter to bring the column to the edge

of the strip 15 containing the graduations 20, so as to run down the column 21 for quickly determining the calculation. The card 23, or several of them, if used, avoid the 5 necessity of carrying the prevailing prices in mind.

The cylinder is also provided with other tables thereon underneath the shorter columns 21. Thus, there are columns 27 for 10 graduations of an exchange table, headed as at 20, by various rates of exchange, such as from 33 to 37 pounds per bushel. There is also a column 29 for bran graduations, and columns 30 and 31 for graduations giving 15 the amount in bushels and pounds of wheat per draft. Other columns 32 contain graduations for tailings for given fractions and the strip 15 is provided along that edge opposite to the edge containing graduations 20, with a column of graduations 26 giving in pounds, say from six to two hundred and fifty, for value derived from the columns 27, 29 and 32. The tables, as shown, are 20 specially useful for exchange of grain for

flour, bran, meal, and the like, and for the 25 sale of such commodities.

Having thus described the invention, what is claimed as new is:—

A calculator comprising a back, upper and lower brackets extending from the back, 30 a cylinder located between and carried for rotation by said brackets, a vertical strip secured at its ends to the brackets and extending along the circumference of the cylinder from one end thereof to the other, the 35 circumference of the cylinder and strip having cooperating graduations, an annular series of radial knobs carried by the cylinder for turning same by hand, said strip having a portion offset away from the cylinder 40 for the passage of said knobs.

In testimony whereof I have signed my name to this specification in the presence of two subscribing witnesses.

LESLIE E. MAUPIN.
